ES PATENT OFFICE.

MAN, OF SAGINAW, TEXAS.

BUGGY-TOP SUPPORT.

tion of Letters Patent. Patented June 29, 1909.

June 12, 1908. Serial No. 438,201.

upper rear portions of the ends of the seat 10, while the longer sides 15 are each formed with a lateral offset 16 and with upwardly directed spaced guards or ears 17—18, the 50 offset bringing the free end of the longer side into the path of the rear bow of the top so that when folded the rear top bow will bear upon the offset portion 16 and between the ears. 55

The member 14—15 thus yieldably supports the top when folded, and protects the top from injury, jars, or jolts produced by running over rough roads or over obstructions. 60

The ears 17—18 prevent lateral displacement of the bows no matter how roughly the vehicle may be handled.

The improved device is simple in construction, can be inexpensively manufactured and applied to vehicle tops of various forms without material structural changes, and effectually prevents jars and concussions incident to the movement of the vehicle from being communicated to the vehicle 70 top.

What is claimed, is:—

As a new article of manufacture, a member formed from a single piece of resilient material and comprising an intermediate 75 longitudinal portion having a lateral offset at one end provided with upwardly directed spaced guards and bent into U-shape at the other end, the U-shaped portion terminating in a flat extremity provided with screw receiving apertures and adapted to be attached to the top edge of the seat side of a vehicle and the offset portion adapted to bear beneath the adjacent "bow" of the vehicle top with the guards at opposite sides of said 85 "bow".

In testimony whereof, I affix my signature, in presence of two witnesses.

Specifica

Application filed J

To all whom it may concern:

Be it known that I, WILLIAM C. PUT a citizen of the United States, residing in Saginaw, in the county of Tarrant, State of Texas, have invented certain new and useful Improvements in Buggy-Top Supp and I do hereby declare the following to be a full, clear, and exact description of the invention, such as will enable others skill 10 to the art to which it appertains to make use of the same.

This invention relates to vehicles having folding tops, and has for its object to provide a simply constructed attachment for yieldably supporting the top, and preventing injury thereto from the jolts and jars incident to the use of the vehicle upon rough roads.

The improved device may be applied to buggies, carriages, automobiles, or any other vehicles having a folding top, but for the purpose of illustration is shown applied to a conventional form of vehicle seat.

With these and other objects in view the invention consists in certain novel features of construction as hereafter shown and described, and then specifically pointed out in the claim, and in the drawings illustrating the preferred embodiment of the invention. Figure 1 is an end view of a conventional form of vehicle seat and a portion of a folding top, with the improvement applied. Fig. 2 is a perspective view of the improved attachment enlarged.

The improved device may be attached to any of the various forms of vehicle seats adapted to the various forms of folding tops in use without material structural changes and for the purpose of illustration is shown attached to a conventional form of buggie seat and folding top, the seat representing 10, and the bows of the top at 11, uniting 12, to the rail 13, of the usual form.

The improved device consists of a resilient member formed in U shape with the sides of unequal length, the shorter side 14, attached by screws or other fastening means to
